MURPHY D. SMITH, OF BIRMINGHAM, ALABAMA, ASSIGNOR TO SAND SPUN PATENTS CORPORATION, OF NEW YORK, N. Y., A CORPORATION OF DELAWARE

BODY PATTERN EXTRACTOR

Application filed August 26, 1931. Serial No. 559,575.

This invention is an improvement in body pattern extractors, and more particularly in a device for starting the body pattern after the ramming of the same.

In foundry practice, the sand for pipes is rammed between the flask and the body pattern, and the pattern is usually extracted from above.

The breaking of the bond between the sand and the body pattern, in the extraction of the same, presents much difficulty.

One of the primary objects of the present invention is the provision in connection with a ramming machine, of means independent of the usual hoist, for initially starting the pattern, that is, for breaking the bond between the sand and the pattern, prior to the removal by the hoist.

Another object is the provision of mechanism capable of attachment to, and used with, the usual type of rammer, without material changes in the same.

With these and other objects in view the invention consists in the construction and novel combination of parts fully described hereinafter, illustrated in the accompanying drawing, and pointed out in the claims appended hereto, it being understood that various changes in the form, proportion, size and minor details of construction within the scope of the claims, may be resorted to without departing from the spirit of the invention.

In the drawing forming a part hereof: Fig. 1 is a longitudinal section of a ramming stool with the flask, patterns, and the like, supported thereon.

Fig. 2 is a detail in section of an alternate construction of starting mechanism.

In the embodiment of the invention shown in Fig. 1, the ramming stool 1 is mounted upon the pier 2, and the flask 3 is supported above the same in the usual position, resting upon the pattern ring 4 and the spigot pattern 5, the latter resting in turn upon the ramming stool.

The flask 3 has a marginal flange 6, and clamps 7 engage this flange and the ramming stool to lock the flask to the stool. Other clamps 8, indicated in dotted lines, are also

provided, engaging the top of the flange and the stool. The body pattern 9 is arranged within the flask, the butt 10 thereof detachably connected with the pattern, set within the spigot pattern 5.

The ramming stool is bolted firmly to the foundation pier 2, as indicated at 11, and the pier is sufficiently large to maintain the equipment accurately in a vertical position. The body pattern is shown in ramming position in the flask, being properly centered by the engagement of the pattern butt 10 within the spigot pattern, and the head pattern 12 is mounted on the body pattern, and properly centered at the top by the stripping plate 13, which also centers the body pattern during the ramming operation. The mechanism just described is the typical tool for the making of molds in the manufacture of cast iron pipe.

Referring to the drawing, it will be seen that the head pattern engages annular shoulders 14 and 14a on the body pattern, and the sand which is indicated at 15, is rammed between the flask and the body pattern, the stripping plate, and also the head pattern, if desired, being removed during the insertion of the greater portion of the sand. The upper end of the body pattern is closed, as shown at 16, and a clevis 17 is connected therewith, the clevis being adapted for engagement by a swivel hook 18 on the cable 19, of a suitable hoist. With this arrangement, difficulty is experienced in breaking the bond between the sand and the body pattern, and the present invention consists in the provision of mechanism in connection with the body pattern, for breaking the said bond, that is, for initially starting the body pattern.

The said mechanism includes a head 20, arranged within an enlargement in the lower end of the body pattern, and bearing against an annular shoulder 21 at the inner end of the enlargement. The head has wings 22 extending transversely of the upper face thereof on opposite sides of a diameter, and these wings are connected to the top of the body pattern and the clevis by means of eye bolts or rods 23. The eyes of the rods are

received between the flanges and engage bolts 24 connecting the flanges. The upper ends of the rods pass through the top 16 of the body pattern and the arms of the clevis, and they are engaged by nuts as shown, to connect the head to the body pattern and to the clevis.

The internal annular enlargement of the body pattern indicated at 25 provides an air chamber or cylinder, in which moves a piston. The piston includes a head 26 having in connection therewith a piston rod 27, which extends downwardly through an opening in the pattern butt to engage with a steel plate 28, resting on the ramming stool. A packing cup 29 of leather or the like, is connected with the piston head, and held in proper position by a plate 30 connected to the head by screw bolts, as shown. Fluid under pressure, as for instance, water or air, is supplied to the cylinder by a pipe 31 extending through the body pattern, and connected at one end with a suitable source of supply. The pipe extends through the closed top 16 of the body pattern, and through the head 20, and it is provided with a suitable valve 32 for controlling the supply.

In operation, the flask with the retaining ring is mounted or centered on the ramming stool. The body pattern is lowered into the flask, being properly centered at the bottom by the spigot pattern. As the body pattern comes to rest, the piston rod 27 extends toward the plate 28. In this position the piston is in the upper position, and the cylinder 25 is ready to receive air for the full stroke of the piston. The centering plate is mounted, and sand is caused to flow between the flask and the body pattern, the head pattern being left off at this time to allow the sand to enter. The sand is rammed by hand, or by pneumatic or jolt rammers, or by any other of the usual processes in the manufacture of cast iron pipe.

When the sand is rammed to a certain height, that is, to near the shoulder 14, the ramming process is temporarily halted, the centering plate is removed, and the head pattern 12 is mounted on the body pattern. The ramming is then continued until the sand is rammed to the level of the top of the head pattern, at which time the stripping plate is mounted and fastened to the flask by wedges 33, as shown. The hook of the pattern hoist is then lowered and engaged with the clevis, and the hoist is operated to take the strain of the body pattern. At this moment, fluid under pressure is admitted to the chamber 25. This causes a downward thrust on the piston head 26 and an upward thrust on the head 20, causing the body pattern to move upwardly, breaking the bond between the body pattern and the sand, thus allowing the hoist to remove the body pattern from

the mold with a nominal amount of power. Either the clamps 7 or 8, or both, may be used, and either type will grip the flask and the ramming stool firmly together, anchoring them to the pier supporting the equipment.

In Fig. 2, an alternate construction is shown, the body pattern 34 having arranged within the lower end thereof a separable chamber 35, which is connected to the top of the body pattern by the rods 36 in the same manner as in Fig. 1. The piston 37 fits loosely within the chamber, and it is encircled by a suitable packing indicated generally at 38, which prevents the escape of fluid under pressure from the chamber.

The piston has a depending rod 39 corresponding to the rod 27 of Fig. 1. Fluid under pressure is supplied by a pipe 40. The operation is precisely the same as in the Fig. 1 construction. The type just described is intended for the use of air, but of course, may be used with other fluid under pressure.

What is claimed as new is:

1. Means to break the bond between the sand and the body pattern of a rammed mold, including a body pattern having at its lower end a chamber for fluid under pressure, and a piston slidably mounted in the chamber and having means to bear against the ramming stool when fluid under pressure is admitted to the chamber.

2. Means to break the bond between the sand and the body pattern of a rammed mold, including a body pattern having at its lower end a chamber for fluid under pressure, and a piston slidably mounted in the chamber and having means to bear against the ramming stool when fluid under pressure is admitted to the chamber, the pattern having a rigid head forming the upper end of the chamber.

3. A body pattern for sand lined molds, having means for initially starting the pattern from the rammed mold, including a cylinder rigid with the pattern and a piston in the cylinder having means extending beyond the cylinder and adapted to bear against a ramming stool, and means for conducting fluid under pressure to the cylinder.

4. In a ramming machine, including a stool, a body pattern having a chamber therein, means for initially starting the pattern after the mold is rammed, comprising a piston in said chamber and having movement therein relative to said body pattern, the piston having a rod extending from the chamber and adapted to engage the ramming stool when the pattern is in place, and means for admitting air to the chamber.

5. In a ramming machine, including a stool, a body pattern, means for initially starting the pattern after the mold is rammed, comprising a piston and a chamber in the body pattern in which the piston moves, the piston having a rod extending

from the chamber and adapted to engage the ramming stool when the pattern is in place, and means for admitting air to the chamber, said chamber being formed by the limiting 5 wall of the pattern and a head rigidly connected with the pattern.

6. In a ramming machine including a stool, and a body pattern, means to initially start the pattern after ramming, comprising a piston 10 slidably mounted in the lower end of the pattern and adapted to engage the stool when the piston is moved downward, the pattern having a chamber in which the piston moves, and means to supply fluid under pressure to 15 the chamber.

7. In a ramming machine including a stool, and a body pattern, means to initially start the pattern after ramming, comprising a piston 20 slidably mounted in the lower end of the pattern, and adapted to engage the stool when the piston is moved downward, the pattern having a chamber in which the piston moves, a head within the pattern permanently connected to the upper end there- 25 of and forming the inner end of the chamber, and means to supply fluid under pressure to the chamber.

Signed at Birmingham in the county of Jefferson and State of Alabama this 20th 30 day of August A. D. 1931.
